UNITED STATES PATENT OFFICE.

WILHELM THALER, OF HEIDENHEIM-ON-THE-BRENZ, GERMANY, ASSIGNOR TO AMERICAN VOITH CONTACT COMPANY, INC., OF NEW YORK, N. Y., A CORPORATION OF NEW YORK.

SEPARATOR.

Application filed January 31, 1923. Serial No. 615,978.

To all whom it may concern:

Be it known that I, WILHELM THALER, a citizen of the Republic of Wurttemberg, Germany, residing at Heidenheim-on-the-Brenz, Germany, have invented certain new and useful Improvements in Separators, of which the following is a specification.

This invention relates to separators or assorting machines, and it particularly relates to a separator for assorting wood pulp, sulphite, straw-pulps, and similar fibrous material, suspended in a liquid, into different grades of fineness.

The object of the invention is to provide means for thoroughly separating the fine fibers from the coarse ones with the least amount of power.

It is a further object of the invention to provide means which will allow the separator to turn in either direction while the water carrying the material, which henceforth is simply called "liquor" is evenly charged to the annular sieve, or sieve mantle.

These objects are accomplished by the following novel features of the invention:

1. By admitting the liquor into the annular sieve by passing the same first through the short entrance zone and then through a longer rear or assorting zone, in both of which water is added all along the zones to dilute the liquor for the purpose of preventing the material from settling on the sieve mantle, thereby clogging the same, and to completely separate the material carried by same into the fine and coarse grades;

2. By a central stationary entrance provided with slits in its orifice, which is arranged in an arch-like shape around the shaft carrying wings, the shaft being journaled in suitable bearings located on the outside of frame whereby stuffing boxes can be dispensed with;

3. By a novel basket or wheel provided with propeller wings and being of simple construction, the hub-plate of the wheel driving the material into the short entrance, or charging zone, and into the longer assorting zone. In the entrance zone the wings of the wheel are reaching close to the entrance, whereby the shock of the entering liquor is reduced and a greater quantity of the liquor is forwarded unto the sieve mantle.

In view of the manner in which the liquor

is passing the machine and of the water added constantly to keep the liquor in properly diluted form, the wings of the propeller wheel can be arranged in straight form in both the axial and radial direction, and may, therefore, run either way.

The separator can be built in a horizontal as well as in a vertical construction, and for the better understanding of my invention I shall describe both forms, reference being had to the accompanying drawings, in which

Fig. 1 represents a vertical longitudinal section of the horizontal construction along line 1—1 of Fig. 2. 70

Fig. 2 is a transverse vertical section along line 2—2 of Fig. 1.

Fig. 3 is a vertical longitudinal section of the vertical construction of the separator. 75

Figs. 4 and 5 are sectional views showing in a somewhat enlarged proportion certain details of the orifice of the stationary entrance.

Like numerals denote like parts throughout the various views.

In my separator an entrance pipe 1 discharges the liquor carrying the material to be separated into a fine and coarse grade through its orifice, having longitudinal slits 85 2 and vertical openings 4 in the front wall 3, into the entrance zone of the separator. The liquor is distributed radially to the shaft 5 and passes along the hub-plate 6 of a bracket member rigidly secured in any of 90 the well known ways to said shaft 5.

To the hub-plate 6 a plurality of wings 7 are secured in a radial fashion around the orifice of the entrance; this wing 7, in co-action with the hub-plate 6, forwards the 95 liquor and passes same along wing 8, of which a plurality projects axially in extension of wings 7 being integral with same. Said wings 7 and 8 act as propellers for warding the liquor both mechanically and by centrifugal force, first through the entrance zone and then through the rear or assorting zone. The peripheral wall of the bracket member is perforated by means of the holes 9 through which water passes, conducted into the inside space of the bracket member by means of the conducting pipe 10 and is discharged through suitable orifices, such as a longitudinal slot 11, towards the 100 perforated wall 9. 110

An annular sieve mantle 14 is secured to the head plates of the standards 15 and 16 within a shell 17 which is supported by the standards 15 and 16. Said shell 17 has a 5 lower outlet 18 for the fine grade and another outlet 19, located sidewardly at the lower edge of the support 16, for the coarse grade of material. Standards 15 and 16 are also provided with journals 12 in which the 10 shaft 5 is rotatively arranged. A pulley 13 serves for imparting motion to said shaft 5.

When the liquor is passing between the hub-plate 6 along wings 7 towards the sieve mantle 14 the material carried by the liquor 15 strikes first against the sieve mantle 14 and part of the material is already there separated into the fine and coarse grade, the fine grade passing through the sieve 14, while the bulk of the material, being now richer 20 in course material, is carried by wing 8 and the flow of the water along sieve 14 to the outlet 19, while the fine grade retained by the course material is flushed with the water along and through sieve 14 and leaves 25 through exit 18. The flow of the water introduced by the conduit pipe 10 keeps the coarse material liquid and prevents the same from settling on the inside of the sieve mantle, thereby clogging same.

30 The vertical construction illustrated by Fig. 3 is easily understood on the ground of the above explanations, the exits for the different grades closely adjoining each other, the exit of the coarse material being 35 located nearer the center, while that for the fine material is pointed in an outward direction.

While I have disclosed my invention by the embodiment described by the constructions explained above, various changes in the construction can be made without deviating from the spirit of the invention or sacrificing the advantages of same, and any such change will be considered as coming 45 within the scope of my invention.

What I claim is:

1. In a separator, in connection with an outside shell, a rotary shaft arranged in bearings on the outside of the shell, an entrance having its orifice centrally arranged in an arch-shaped manner above the rotary shaft, a basket having a perforated periphery extending from a hub-plate rigidly connected to said rotary shaft, a plurality of 50 wings extending radially from the shaft on the hub-plate of said basket, a plurality of wings extending axially on the basket along its perforated periphery and being integral with the wings on the hub-plate, a sieve 55 mantle mounted on the shell around the perforated basket and wings thereon, means to supply water to the inside space of the basket along its peripheral side, an outlet in the outside shell below the sieve mantle, 60 an outlet in the outside shell communicat-

ing with the inside space of the sieve mantle, and means for rotating said shaft.

2. In a separator, an outside shell provided on its outside with bearings, a rotary shaft supported in said bearings and extending centrally through said shell, a basket having an end wall connected to said shaft and a perforated periphery extending from said end wall and provided with straight wings mounted both radially and axially on the outside of the end wall and perforated periphery of said basket and being co-extensive with each other, a sieve mantle mounted on the outside shell and arranged around the perforated basket, means to supply water in the inside space of the perforated basket along its peripheral side substantially from the end wall of the basket to the open end thereof, an outlet on the outside shell below the sieve mantle, an outlet on the outside shell communicating with the inside space of the sieve mantle, and means for rotating said shaft. 75

3. In a separator for separating finely divided material, suspended in a liquid, through a sieve mantle, into different grades, a rotary cylindrical basket open at one end and having an imperforate wall at the other end thereof and provided with perforations through its cylindrical peripheral wall, straight wings mounted radially from the end wall and axially along the cylindrical wall outside of the basket, and means for rotating said basket in either direction. 80

4. In a separator for separating finely divided material, suspended in a liquid, through a sieve mantle, into different grades, a rotary perforated basket having straight wings mounted both radially and axially on its outside, a shaft upon which said basket is mounted for rotating it, and an entrance having an arch-like shape centrally located around the shaft whereby the liquid material will be evenly distributed over the sieve mantle by the wings on the basket. 100

5. In a separator for separating finely divided material suspended in a liquid through a sieve mantle, a rotary perforated basket having straight wings mounted both radially and axially on its outside, and means adjacent to the peripheral wall of the basket for supplying water through the basket and into the inner side of the sieve mantle. 110

6. In a separator for separating finely divided material suspended in a liquid, through a sieve mantle, into different grades, a stationary liquid supply entrance centrally located around the shaft having axial slits in the upper and side portions of its peripheral wall, all communicating with the said liquid entrance. 125

7. In a separator for separating finely 130

- divided material suspended in a liquid, through a sieve mantle, into different grades, a stationary liquid supply entrance centrally located around the shaft having axial slits 5 in the upper and side portions of its peripheral wall, a plurality of enlarged openings through the innermost end of said entrance, each communicating with one of said slits, and all openings communicating with 10 the said liquid entrance.
8. In a separator for separating finely divided material suspended in a liquid, through a sieve mantle, into different grades, a rotary shaft carrying a hub member and 15 a perforated cylindrical peripheral member extending from the periphery of the hub, radial wings mounted on the hub and wings mounted axially along the perforated periphery co-extensive with the first said 20 wings, and a stationary entrance for the liquid mounted concentric with said shaft and having peripheral slits therein for feeding the liquid into the separator between said wings on said hub.
25. 9. In a separator for separating finely divided material suspended in a liquid, a rotary member carrying a plurality of radially arranged wings, and a stationary entrance for feeding the liquid mounted concentric 30 with said shaft arranged between it and the wings carried on the shaft and having a number of axially arranged slits in its periphery, whereby liquid fed therethrough will be successively interrupted in its passage outward by the rotating wings.
35. 10. In a separator, in connection with an outside shell, a rotary shaft arranged in bearings outside the shell, a stationary entrance extending into the separator around 40 the said rotary shaft, said entrance having orifices for directing the flow radially outward from the shaft, a hub plate rigidly fastened on said rotary shaft beyond the end of said entrance member, a plurality of 45 wings on said hub plate extending radially outward from the periphery of said entrance member on the entrance side of the hub plate, wings on the opposite side of said
- hub plate integral with said radial wings and extending beyond the hub plate and axially from the outer ends of said radial wings, means for supplying water in the space between said rotary shaft and said axially extending wings and directing the water outward along the sides of the wings, a sieve mantle mounted on the outside shell and surrounding said wings, outlets communicating with the inner and outer sides of said sieve mantle, and means for rotating the shaft.
- 50 55 60
11. In a separator, in connection with an outside shell, a rotary shaft arranged in bearings outside the shell, a stationary entrance extending into the separator centrally arranged in an arch shaped manner around the said rotary shaft, said entrance having orifices extending over that part of its entire length projecting into the interior of the separator and openings in the front wall of the entrance extending inwardly from 70 said orifices, a hub plate rigidly fastened on said rotary shaft beyond the end of said entrance member, a plurality of wings on said hub plate extending radially outward from the periphery of said entrance member on the entrance side of the hub plate, wings on the opposite side of said hub plate integral with said radial wings and extending beyond the hub plate and axially from the outer ends of said radial wings, means for 75 supplying water in the space between said rotary shaft and said axially extending wings and directing the water outward along the sides of the wings, a sieve mantle mounted on the outside shell and surrounding said wings, an outlet on the outside shell 80 communicating with the outer side of the sieve mantle, an outlet on the outside shell communicating with the inner side of the sieve mantle, and means for rotating the shaft.
- 85 90
- In testimony that I claim the foregoing as my invention, I have signed my name hereunder.

WILHELM THALER.
